MULTICCOMPARTMENT CONTAINER

Jack R. Belsinger, Atlanta, Ga., assignor to
 Belsinger, Inc., Atlanta, Ga., a corporation of
 Georgia

Application June 17, 1947, Serial No. 755,158

7 Claims. (Cl. 229—15)

1

This invention relates to improvements in containers comprising outer and inner members and which may be utilized to hold differing bulk commodities in separate compartments.

A feature of the invention is the provision of a dual container which comprises a composite whole that can be sealed against theft or separation of its parts, and which has two compartments at its interior and permits the separation of the commodities therein prior to exposure of these commodities.

Another feature of the invention is the provision of a container having plural inner members which can be individually filled and delivered to an assembly point at which they are combined with outer members serving to close the same, and wherewith these outer members can be sealed together to maintain the structure against accidental exposure of the contents and against the stresses incident to transport.

A further feature of the invention is the provision of a dual container in which inner members are provided for individual filling and delivery to an assembly point, at which these members are then individually supplied with outer closure pieces telescoping therewith, wherewith the outer members interfit and abut one another and the inner members provide a strong intermediate partition within the total package.

With these and other features as objects in view as will appear in the course of the following specification and claims, illustrative forms of practice are shown on the accompanying drawings in which:

Fig. 1 is a perspective view of a filled and sealed container of the instant type.

Figs. 2, 3 and 4 are views on a similar scale, indicating the banks employed for forming the container of Fig. 1.

Figs. 5, 6, 7, 8, and 9 are perspective views indicating the manner of filling and assembling the container.

Fig. 10 is a perspective view of a modified form of the container.

Fig. 11 is an exploded view in perspective, showing the individual parts in their respective relationships to one another, as employed in the modified form of Fig. 10.

Fig. 12 is a perspective view, in part corresponding to Fig. 9, of the modified form of container, shown during separation of the two half-containers.

Figs. 13, 14, 15, and 16 are views, on a similar scale, indicating the blanks employed in forming the container of Figs. 10-12.

2

Fig. 17 is a perspective view, indicating the manner of folding and assembly of a container member.

Fig. 18 is a perspective view of a modified manner of securing the parts of a container member.

In these drawings, the container is shown with two inner members and two outer members which telescopingly fit over the inner members and abut against one another at their own free edges.

10 In Fig. 1, the outer structure of the container is provided by a longer outer member A and a shorter outer member B having their edges abutting at the dotted lines E and being sealed and held against separation by a closing tape T which 15 may be of the usual cemented type and overlaps the abutting edges and is secured to the several faces of the members A, B, therewith extending along the individual common planes formed by the side walls at these abutting edges.

20 The longer outer member A is formed from a blank as shown in Fig. 2, with the vertical wall portions 10, 11, 12, 13 formed integrally in the sheet and separated from one another by the fold lines 14 which may be formed as usual, when 25 the blank is made of corrugated board, by scoring to assist and locate the lines of fold. A flange 15 is joined integrally in the blank by a similar fold line 14. Each of the vertical walls 10-13 is also joined to an individual end flap 16, 17, 18, 30 19 across the fold lines 20, which likewise may be formed by scoring: these fold lines are indicated as offset successively with respect to one another, corresponding to the thickness of the material used, so that the end flaps can be folded down to 35 form two planes. The end flaps are separated from one another by cuts 21.

The shorter outer member B is formed from a blank as shown in Fig. 3, which is of the same general form as the blank of Fig. 2 except that 40 the vertical wall distance is less. The corresponding parts are identified by the same reference numerals as in Fig. 2, with the addition of the suffix letter *b*, wherewith the vertical wall 10b corresponds to the vertical wall 10 of Fig. 2, etc.

45 The internal members for Fig. 1 are formed from a blank as shown in Fig. 4, which is likewise similar to the blank of Fig. 2, except that the vertical height or depth is substantially the mean 50 of the heights of the blanks of Figs. 2 and 3, that is, the vertical height for a wall in the blank of Fig. 4 is slightly less than one-half the combined height of the vertical walls in Figs. 2 and 3, the lesser distance being essentially equal to twice 55 the thickness of the material employed for the

blank of Fig. 2. For comparison, the same reference numerals, with the suffix *c* are used for Fig. 4, wherewith the wall 10c corresponds to the wall 10 in Fig. 2; etc.

In forming the container of Fig. 1, one each of the blanks 2 and 3, and two of the blanks of Fig. 4 are used. These blanks can be made and shipped from the paper factory in the flat; and can be assembled at the packing plant by the usual simple stapling equipment. For assembly, as indicated in Figs. 17, the blank (e. g. that of Fig. 2) is folded about the fold lines 14, so that the end flange 15 is brought against the wall 13, and then is stapled thereto to form a tubular structure of polygonal (illustratively square) cross-section. For the inner containers formed from the blank of Fig. 4, it is preferred to have the flange 15c on the inside, to give smooth outer surfaces; while for the outer members, the flange 15 or 15b is folded on the outside, to give smooth inner surfaces.

This tubular structure then has the opposed end flaps 17, 19 folded down into a plane; and then the end flaps 16, 18 are folded thereover into a second plane. Thus, the two layers of end flaps fit closely together and can be joined by the stitching machine in the usual fashion, so that a strong and rigid end is produced.

For packing and sealing the container of Fig. 1, two of the inner members are utilized, and these may be loaded individually with oranges and grapefruit, for example, at separate loading tables. When filled, they can then be taken to a place at which the final closing and sealing is to be accomplished. These operations are indicated in Figs. 5 to 9. An inner member C (Fig. 5) is shown as loaded with a commodity such as large oranges. It will be noted that the loading is accomplished with the closed and stapled end flaps 16c, 18c resting upon a bench or floor, and that there is easy access for the operator in placing the articles in position, as the top or upper end is entirely open and has no flaps or other structures to obstruct the view and facility of loading by hand or machine. When this container C is delivered to the closing floor, the short outer member B is placed over and telescoped therewith. The selection of dimensions between the fold lines 14b of Fig. 3 and the fold lines 14c of Fig. 4 is determined by the thickness of material, so that a tight sliding fit is afforded. The short outer member B has a lesser vertical height than the corresponding walls of the inner member C, so that the inner surfaces of the flanges 17b, 19b engage the free or upper edge of the inner member C before the free or lower edges of the outer member B come in contact with the floor (Fig. 6). Thus, there is assurance of abutment of upper edges of the inner member C with the lower surface of the outer member B, under the pressure for the telescoping.

The assembly as shown in Fig. 6 is now inverted, an operation which is permitted because the contents are now enclosed at all sides. In this inverted position, as shown in Fig. 7, the inner member C projects above the free edges of the side walls of the outer member B.

A second inner container D is then placed on the inverted assembly B, C, as shown in Fig. 8. Since the containers C and D are identical in horizontal section, the alignment is easy; and it will be noted that the only lifting of weights is that of moving the individual containers or inner members C, D with their contents. It is assumed that the inner member D is filled with

smaller oranges to level-full condition. In the illustrative form, the horizontal cross-section of the inner members C and D is square; and it is preferred in placing the inner member D in position to have the abutment line of its flanges 16c, 18c at right angles to the corresponding abutment line of the inverted inner member C. Thus, the inverted member C has two thicknesses of corrugated board forming its upper and closing end (Fig. 7), these thicknesses being stapled together and forming a rigid partition structure within the total container. Correspondingly, the two thicknesses for the inner member D are joined fixedly together and cooperate in forming the stiffening partition within the total container, this effect being increased by having the successive layers located with their abutment edges lying at right angles to one another.

The longer outer member B is now placed over and in alignment with the inner member D, and telescoped thereon by simple downward sliding movement as indicated by the arrow M in Fig. 9. When this longer outer member B has been moved downward until its lower edge passes the lower surface of the closing flaps 16c, 18c of the inner member D, the outer member B now telescopes over the upper end of the inner member C, until finally the free or lower edges of the outer member B come into abutment with the corresponding and mating edges of the outer member A, whereupon the sealing tape T may be applied by the easy operation of wetting its adhesive, for example, and merely passing a sufficient length around the container while it stands on the floor with all sides exposed for the operation.

Thus, in the closed and sealed container, the double thicknesses at the end walls are stapled tightly together and provide strong reinforcing end structures for the packing. Likewise, the quadruple thicknesses, stapled two-by-two together in making the inner members, provide a strong partition within the package to resist bulging of the walls by pressure of the contents against them. The abutment line between the outer members is spaced along the package from the abutment plane between the inner members C, D, thereby reducing any tendency of the weight of the contents to cause relative shifting of the members and shearing of the tape T, or shearing of the walls at the plane between the inner members C, D.

The package has large areas exposed for reception of identifying, advertising, and invoicing markings. The surfaces are acceptably smooth under the regulations concerning the form and securing of corrugated and solid fiber cartons.

When such a package is received by a commission merchant after transportation, it can be opened by simple slitting of the tape T along the lines of the abutment of edges of the outer members A, B. The individual halves can then be separated, and thus two separate closed packages are provided. In the illustrative form, where the inner members CD are identical, and when the same are initially filled with the same contents, the receiver thus has two separate packages which can be handled and distributed independently of one another and each containing half the quantity of the original shipment package.

The manner of opening each of these individual compartments is obvious upon simple inspection by the receiver. The half-package with the inner member C is placed in the position as shown in Fig. 6, and the outer member B is pulled

upward and removed, thereby exposing the contents as shown by Fig. 5. The half-carton provided by the inner member D and outer member B is likewise obviously to be opened by inverting it so that the inner member D slides downward and rests upon the floor, whereupon the outer member B can be lifted and removed. It will be noted that even if the unpacker ignorantly attempts to separate the half-package of Fig. 7, by lifting the inner member C, yet the goods are held by the outer member B; and a similar condition exists with respect to the assembly of the inner member D and its outer member A, although in this case the usual positioning of the exposed surface of the inner member D, formed by the end flaps 17b, 19b, indicate that inversion is preferable, along with the usual condition that the fingers can not be engaged with the inner member D to raise it upwardly.

A modified form of construction is shown in Figs. 11-16. In this, for simplicity, it is assumed that the inner containers CD are substantially identical with those described above and formed from blanks as in Fig. 16. The outer members consist of a member E having a lesser wall height, and a member F having a greater wall height. The outer member E is formed from one end of the blanks shown in Figs. 13 and 14. The blank of Fig. 14 is of simple rectangular form, having the vertical wall portions 10e, 11e, 12e, 13e joined by the fold lines 14e as before, and also includes the end flange 15e. This structure is folded into a tube, and the end flange 15e joined to the vertical wall 13e as described above. The end surface for the outer member is provided by a blank as shown in Fig. 13 having the central field 30 joined by the fold lines 31, 32 with the marginal flanges 33, 34. The flanges 33 are likewise joined by fold lines 35 with the corner flaps 36. The blank of Fig. 13 is assembled with a tube formed from a blank as in Fig. 14, by bending the flanges 33, 34 until they fit flat against the outer faces of the tube, with the corner flaps 36 turned inside the corresponding flanges 34. The parts are then stitched as indicated in Figs. 10, 11, and 12, so that a strong and rigid end structure is provided. The longer outer member F is formed from a blank as in Fig. 13, and from a blank (Fig. 15) having the same arrangement and positioning of parts and score lines as in Fig. 14 but of a greater wall height dimension; that is, the distance along a score line 14f from edge to edge is less than along the score line 14e of the member E. The assembly of member F is performed as for the member E.

The method of packing, sealing and opening of this container is the same as described for the first modification, with reference to Figs. 5 to 9. In this form of arrangement, the end surfaces are totally smooth, and the filled container can be easily slid around on a floor.

It is preferred, in forming the outer members A, B or E, F to make them symmetrical, or "right-and-left," so that the corner flanges 15, 15b or 15e, 15f abut one another, as shown in the figures, as therewith the sealing tape T lies in planes in its contacts with the various outer wall areas.

The blanks and structures described above utilize overlapping of flaps and walls, and stitching of the overlapped portions to form tubes or partition ends. It is also feasible to employ sealing tapes for one or more connections. In Fig. 18 is shown, illustratively, the assembly of an inner container member from a blank as shown by Fig.

4, but lacking the end flap 15c. This blank is first folded into a tube, and its walls 10c and 13c connected by a tape 40. The end flaps 17c, 19c, 18c are folded down, and then the end flaps 16c, 18c. 5 A sealing tape 41 is then applied over the abutment line of flaps 16c, 18c to secure these, and the ends of tape 41 are secured to the side walls 10c, 12c to hold the flaps in their plane positions.

When employed for fruits and other articles 10 where ventilation is desirable, the blanks are provided with apertures 45 at points which are in alinement in the inner and outer members when the containers are closed and sealed.

It is obvious that the invention is not limited 15 to the forms of construction shown; but they may be employed in many ways within the scope of the invention claims.

I claim:

1. A container having two outer members and 20 two inner members, each of said members having side walls and a secured closing end, the outer members having identical cross-sections so that their free edges can be brought into abutment, the inner members having a telescoping fit with- 25 in the outer members and each having its free edges closely adjacent the closing end of one of the outer members and its closing end adjacent the open end of said one outer member, the closing ends of the inner members being in abutting relation to one another and spaced from the closing 30 ends of the outer members by distances equal to the depths of said inner members, the side wall height of one outer member being less than the side wall height of the inner member located therein, and the side wall height of the other outer member being greater than the side wall height of the other inner member so that said other outer member is in telescoping engagement 35 with both inner members, whereby said abutment of a side wall on one outer member with the corresponding side wall on the other outer member is spaced from the closing ends of the inner members.

2. A container having two outer members and 45 two inner members, each of said members having side walls and end flaps connected therewith and folded into contact in planes and secured together to provide a closing end, the outer members having identical cross-sections at their free edges so that such edges can be brought into abutment, 50 the side walls of one outer member being longer than the side walls of the other outer member, said inner members being each telescopingly positioned in a corresponding outer member with its own closing end forming a closure for the open end of the outer member and spaced from the free edges thereof, the longer outer member being also telescopingly engaged around the portion of the inner member which projects from the shallower outer member, said outer members providing essentially plane surfaces across the lines of edge abutment thereof, and a sealing tape extending across the abutment and joined to said outer members at both sides of said abutment.

3. A container as in claim 2, in which the end flaps of the inner members form two layers with the layers tightly secured together for preventing change of the cross-section of the members adjacent the closing ends formed thereby, the 70 outermost layer being formed by flaps connected to opposite side walls and each flap having an edge substantially parallel to the line of connection thereof to the corresponding side wall, the two inner members being positioned in the outer members with said flap edges of one inner member at

right angles to the flap edges of the other inner member.

4. A container as in claim 2, in which the side walls of the inner and outer members have ventilating apertures which are in alinement in the telescoped and assembled position of the parts with the edges of the outer members in abutment.

5. A container having a pair of outer members of identical cross-section and each having side walls and a closing end, the side walls of the two outer members having their corresponding free edges in abutment in the closed condition of the container whereby to provide substantially plane surfaces across the lines of abutment; inner members each having an external cross-section for telescopic sliding fit in a said outer member, and each having side walls and a closing end; the depths of the outer members and of the inner members being different so that the said abutments are not in the same plane as the ends of inner members when telescopingly assembled into respective outer members, the members being so constructed and arranged that one outer member has its free edges projecting in fully telescoped condition a distance beyond the end of an inner member equal to the distance of projection of an inner member beyond the free edges of the other outer member and surrounds parts of each inner member; said inner members being positioned with their closing ends in juxtaposition and thereby forming a stiffening transverse partition within and spaced from the closing ends of the outer members and from said abutments; and sealing means extending across said abutments and secured to the outer members at each side of each abutment.

6. A container as in claim 5, in which there are two inner members of rectangular section each formed from a blank providing side walls with an end flap connected to each side wall, said end flaps being located in two layers with each layer formed by the end flaps connected to opposite side walls, said layers being stitched together to provide the closing end; the said inner members being positioned in the outer members with their closing ends contacting one another whereby to provide a partition composed of four thicknesses located between and remote

8
from each of the closing ends of said outer members.

7. A container having a pair of outer members of identical cross-section and each having side walls provided by a tubular structure and having a closing end formed by a field having flaps joined to its edges and lying against the outer surfaces of the side walls and secured fixedly thereto, the side walls of the two outer members having their corresponding free edges in abutment in the closed condition of the container whereby to provide substantially plane surfaces across the lines of abutment; inner members each having an external cross-section for telescopic sliding fit in a said outer member, and each having side walls and a closing end; the depths of the outer members and of the inner members being different so that the said abutments are not in the same plane as the ends of inner members when telescopingly assembled into respective outer members, the members being so constructed and arranged that one outer member has its free edges projecting in fully telescoped condition a distance beyond the end of an inner member equal to the distance of projection of an inner member beyond the free edges of the other outer member; said inner members being positioned with their closing ends in juxtaposition and thereby forming a stiffening transverse partition within and spaced from the closing ends of the outer members and from said abutments; and sealing means extending across said abutments and secured to the outer members at each side of each abutment.

35 JACK R. BELSINGER.
